UNITED STATES PATENT OFFICE.

CHARLES EDWARD WISE, OF BROOKLYN, NEW YORK.

BOOK-COVER.

No. 848,714.

Specification of Letters Patent.

Patented April 2, 1907.

Application filed June 2, 1906. Serial No. 319,891.

To all whom it may concern:

Be it known that I, CHARLES EDWARD WISE, a citizen of the United States, residing at Brooklyn, in the county of Kings and State of New York, have invented new and useful Improvements in Book-Covers, of which the following is a specification.

My invention is advantageously used on order-books, check-books, receipt-books, and similar blank forms which are used with a stub and where a date-indicator or calendar should be before the user.

This cover may be made with a spring-back to temporarily hold the leaves or be bound permanently thereon.

The under or back side of the cover is made the full size of the leaves of the book, and the top side of the cover is made narrow to cover the stubs only. A calendar for any desired period is secured upon or attached to this narrow side of the cover by any suitable means.

The invention is fully illustrated in the accompanying drawings, letters of reference indicating corresponding parts in the views.

Figure 1 is a plan of the invention with parts of the top cover broken away. Fig. 2 is a vertical cross-section on line $x-x$ of Fig. 1.

The letter A designates the back of a book-cover, B the under side of the cover, and C the upper side of the cover. The side B is made the full size of the leaves D of the book; but the upper side C is made quite narrow.

In the drawings the leaves D are shown to be printed as receipt-blanks, having their stubs d beneath the cover C. A flat recess or pocket c is formed in an edge of the cover C, extending nearly to the opposite edge of said cover, and an opening c' is made in the outer face of said cover C.

E indicates a calendar adapted to be inserted in said pocket c and to be visible through the opening c' . When the dates of the calendar have been passed, the calendar is drawn out from the pocket and a new one inserted.

The advantages of this device are apparent in the saving of time, securing accuracy, and expediting business.

Having now described my invention, what I claim, and desire to secure by Letters Patent, is—

Leaves printed with stubs at one side, a cover for said leaves having its under side the full size of said leaves and its upper side the size of the stubs only, a flat pocket in said stub-cover, an opening through the outer face of said stub-cover into said pocket and a removable calendar in said pocket visible through said opening as described.

In testimony whereof I affix my signature in presence of two subscribing witnesses.

CHARLES EDWARD WISE.
